US00D749589S

(12) **United States Design Patent**
Ferguson et al.

(10) **Patent No.:** **US D749,589 S**
(45) **Date of Patent:** **** Feb. 16, 2016**

(54) **BLUETOOTH LOW ENERGY BEACON**

(71) Applicant: **EBAY INC.**, San Jose, CA (US)

(72) Inventors: **Hill Ferguson**, San Jose, CA (US); **John H. Granberry**, Los Altos, CA (US); **Satish Govindarajan**, Los Altos, CA (US); **Kent C. Griffin**, Mountain View, CA (US); **Yves Behar**, San Francisco, CA (US); **Arthur Kenzo Debaigue**, San Jose, CA (US)

(73) Assignee: **PAYPAL, INC.**, San Jose, CA (US)

(**) Term: **14 Years**

(21) Appl. No.: **29/516,367**

(22) Filed: **Jan. 30, 2015**

Related U.S. Application Data

(63) Continuation of application No. 29/466,537, filed on Sep. 9, 2013, now Pat. No. Des. 723,566.

(57) **CLAIM**

The ornamental design for a bluetooth low energy beacon, as shown and described.

DESCRIPTION

FIG. 1 is a perspective top view of a bluetooth low energy beacon showing our new design;

FIG. 2 is perspective bottom view thereof;

FIG. 3 is a top view thereof;

FIG. 4 is a front end view thereof;

FIG. 5 is a back end view thereof;

FIG. 6 is a bottom view thereof;

FIG. 7 is a side view thereof; and,

FIG. 8 is another side view thereof.

In the drawings, the broken lines depict environmental subject matter only and form no part of the claimed design.

1 Claim, 4 Drawing Sheets
